UNITED STATES PATENT OFFICE.

DAVID FRANK, OF NEW YORK, N. Y., ASSIGNOR OF ONE-HALF TO JOHN TROUNSTINE, OF SAME PLACE.

DESIGN FOR A CORNER-POST FOR BEDSTEADS.

SPECIFICATION forming part of Design No. 33,964, dated January 22, 1901.

Application filed December 26, 1900. Serial No. 41,165. Term of patent 7 years.

To all whom it may concern:

Be it known that I, DAVID FRANK, a citizen of the United States, residing at New York, (Brooklyn,) Kings county, State of New York, have invented and produced a new and original Design for a Corner-Post for Bedsteads, of which the following is a specification, reference being had to the accompanying drawing, forming a part thereof, and in which is represented a side elevation of a corner-post for bedsteads bearing and incorporating my design.

The leading feature of my design consists of the form and ornamental configuration of the corner-post substantially as shown, the special novel feature being the ornate upper end of said post.

In the drawing, A designates the corner-

post, which comprises the body B and ornamental upper end portion C, the latter being the distinctive part of the post and bearing the conventionalized foliate ornamentation D D, as shown. The said upper end portion C has a laterally-curved upper extremity E, which adds to the ornamental effect.

What I claim is—

The design for a corner-post for bedsteads, substantially as shown and described.

Signed at New York, (Brooklyn,) in the county of Kings and State of New York, this 22d day of December, 1900.

DAVID FRANK.
